UNITED STATES PATENT OFFICE

2,517,921

LEAK TESTER FOR HEAT EXCHANGERS

James R. Phares, Arcadia, Calif., assignor to C. F. Braun & Co., Alhambra, Calif., a corporation of California

Application February 24, 1947, Serial No. 730,338

6 Claims. (Cl. 73—40)

1

This invention relates to a fluid test device and is particularly directed to apparatus for locating defective joints between a plurality of heat exchanger tubes and a cooperating tube sheet, and for locating defective tubes.

The principal object of this invention is to provide a test device of this type, which may be releasably connected to an open-ended housing, from which a tube bundle and tube sheet project, and having an annular sealing means cooperating with an exposed side face of the tube sheet and having an opening exposing the major portion of the tube sheet for inspection.

Another object is to provide a device of this type, which is adjustable for cooperation with various types of heat exchangers and which will accommodate variation in the distance between the exposed side face of the tube sheet and the open end of the housing.

Another object is to provide a device of this type, which is simple in design and convenient to use and which avoids any requirement for expandable plugs for tube-sheet bolt holes, or filler blocks to cooperate with notches which may be present in the periphery of the tube sheet.

A further object is to provide a test device of this type, which may be utilized at the maximum test pressure for which the heat exchanger is designed.

Another object is to provide such a test device which may be left in position while a defective joint is re-rolled, or while a defective tube is plugged or replaced.

Other objects and advantages will appear hereinafter.

In the drawings:

Figure 1 is a perspective view of a portion of a heat exchanger showing a preferred form of test device embodying my invention mounted in operative position on the heat exchanger.

Figure 2 is a longitudinal sectional view of a portion of the device shown in Figure 1.

Figure 3 is an exploded view of the various parts of the test device embodying my invention, before installation on the heat exchanger housing.

Referring to the drawings, the heat exchanger shown in Figure 1 is preferably of the type disclosed in the co-pending application of Arthur M. Whistler and Milton S. Nehls, filed July 10, 1946, Serial No. 682,656. Such devices are commonly used in oil refining and other industrial and chemical processes. The term "heat exchanger" is used in its generic sense to cover a heater, cooler and condenser, or other apparatus of this design in which heat is added or taken from fluid.

2

passing through the device. In the construction of such heat exchangers, a tube bundle, generally designated 10, includes a large number of individual tubes 11, which extend axially through the heat exchanger housing 12. For clarity of illustration, only a few tubes are shown in Figures 2 and 3 of the drawings; but it is to be understood that the housing 12 is substantially filled by a large number of such tubes. The ends of the tubes 11 are shown at 13, in Figure 1.

A tube sheet at each end of the housing is provided with a large number of holes for reception of the individual tubes. Only one of the tube sheets is fixed relative to the housing. The other tube sheet is allowed to float with respect thereto, to accommodate variation in length due to thermal expansion and contraction. The floating tube sheet is identified in the drawings by the numeral 14, and the individual holes for reception of the tubes 11 are designated 15. A fairly tight fit is formed between each tube 11 and its hole 15, and in order to insure that leakage shall not occur along the joint, each tube 11 is expanded within its respective hole 15 by means of

25 any one of a number of tube expanders commercially available and well known in the art. The purpose of the test device embodying my invention is to test, simultaneously, all of the joints between the tubes 11 and the tube sheet holes 15, in order to locate any defective joint or joints, as well as to locate any leaky tubes.

The housing 12 is provided with an end flange 16 having a plurality of apertures 17 formed therethrough. Normally, this flange 16 and series of apertures cooperates with another flange on a body cover, not shown, for closing the open end 18 of the housing 12. The tube bundle 10 ordinarily projects from the open end of the housing 12 and the tube sheet is positioned at the extreme end of the tube bundle 10. The exposed side face 19 of the tube sheet 14 may vary somewhat in position with respect to the open end 18 of the housing 12, depending on the particular design of the heat exchanger. Furthermore, the tube sheet 14 may be provided with openings 20 near the outer periphery thereof, through which connecting bolts, not shown, normally pass for connecting a floating head, not shown, to the tube sheet 14. Furthermore, the tube sheet, on some designs, may be notched at intervals around the periphery thereof for cooperation with flow directing baffles or plates, not shown.

Provision of the openings 20 of the peripheral notches, not shown, make it difficult to establish a sealing connection with the periphery of

the tube sheet and although such attempts have been made in prior structures, the disadvantages of employing expanding plugs for the openings 20 or filler plugs for peripheral notches makes the device unwieldy and cumbersome to use in practice.

In accordance with my invention, a seal ring 21 is provided on the exposed side face 19 of the tube sheet 14, which is relatively large in diameter, so that all of the openings 15 are positioned 10 radially inwardly of the ring 21. The ring 21 is mounted in a recess 22 provided on a radially extending flange 23 carried on a sleeve member generally designated 24. Formed integrally with the flange 23 is a cylindrical projection 25, which encircles the tube sheet 14 and which is received in sliding relation within a bore 26, formed axially in the body member, generally designated 27. The body member may be releasably connected to the end flange 16 on the housing 12 by means of the hook bolts 28, which extend through the apertures 17, which are provided with cooperating nuts 29. A seal ring 30 is provided between the body member 27 and the end flange 16 and is adapted to be compressed into sealing relationship by means of the bolts 28 and nuts 29.

Means are provided for establishing a fluid-tight connection between the annular projection 25 on the member 24 and the cylindrical bore 26 of the member 27. As shown in the drawings, 30 this means includes an annular recess 31 formed in the member 27 and adapted to receive a compressible sealing ring 32 and a metallic follower ring 33. A plurality of crowder bolts 35 are threaded through a portion of the member 24 and each is provided with a contacting portion 34 adapted to engage the metallic follower ring 33. A series of studs 36 are mounted in the body member 27 and project axially therefrom through holes 37 provided in the sleeve member 24. Nuts 38, which are mounted on the studs 36, provide means whereby the sealing ring 21 may be placed under compression between the tube sheet 14 and the flange 23.

The seal ring 30 is placed in position on the body member 27 and the latter is then moved adjacent the open end 18 of the housing 12. Hook bolts 28, which engage over a flange 39 on the body member 27, serve to hold the body member 27 and flange 16 in alignment and to 50 clamp the seal ring 30 therebetween. The seal ring 32 is then placed in position within the recess 31 and the metallic follower ring 33 is placed in position behind the seal ring 32. The sleeve member 24 is then moved axially into place, aligning the holes 37 over the axially projecting studs 36. The projection 25 extends within the bore 26. The seal ring 21, carried on the flange 23 of the sleeve member 24, is received in an annular groove 40 positioned on the exposed side face 19 of the floatinghead tube sheet 14. Nuts 38 are then threaded on the bolts 36 to clamp the seal ring 21 between the flange 23 and the tube sheet 14. The seal ring 32 is then expanded into sealing relation to establish a fluid-tight joint between the projection 25 and the bore 26. This is accomplished by threading the crowder bolts 35 through the sleeve member 24.

The interior of the housing is then subjected to fluid pressure and this may be accomplished by admitting water or other fluid under pressure through the inlet fitting 41. For some types of service, it has been found desirable to inject a gas for testing purposes. The various parts of 70

the test device embodying my invention are designed with sufficient strength to permit the test to be carried out at the full test pressure for which the heat exchanger is rated. Any defective joints between the tubes 11 and the tube sheet 14 will permit water (or gas) to leak from the interior of the housing and pass outwardly to the exposed surface 18 through the defective joint. Since the major portion of the end surface 19 is exposed for inspection through the center opening 42, in the flange 23, the location of the defective joint or joints is readily located by visual inspection if water is used, or by other known methods if a gas is used. Thus, as shown in Figure 1, leakage occurring around any one of the ends 13 of the individual tubes 11 indicates a defective joint. Fluid escaping from the end of any particular tube shows that there is a leak in the wall of that tube. Defective tubes may then be replaced or plugged and defective joints may be expanded into a tighter fit with the particular hole through the tube sheet 14, without removing the test device.

Having fully described my invention, it is to be understood that I do not wish to be limited to the details herein set forth, but my invention is of the full scope of the appended claims.

I claim:

1. In a device for pressure testing the tubes of a heat exchanger and for locating defective joints between the tubes and a tube sheet, the tubes being positioned within a housing, the combination of: an annular body member adapted to be removably secured to an open end of the housing, the body member having an axial bore, a sleeve member mounted for axial movement relative to the body member and provided with an annular projection slidably received within the bore, and means for establishing a sealed connection between the sleeve member and the tube sheet, and separate packing means encircling the projection for establishing a fluid-tight joint between the sleeve member and the body member.

2. In a device for pressure testing the tubes of a heat exchanger and for locating defective joints between the tubes and a tube sheet, the tubes being positioned within a housing, the combination of: an annular body member adapted to be removably secured to an open end of the housing, a sleeve member mounted for axial telescopic movement within the body member and provided with an annular flange extending radially inwardly, means for establishing a sealed connection between said flange and an exposed side face of the tube sheet, said means including cooperating parts on the body member and sleeve member for moving the sleeve member axially toward the tube sheet, and means for establishing a fluid-tight joint between the sleeve member and the body member.

3. In a device for pressure testing the tubes of a heat exchanger and for locating defective joints between the tubes and a tube sheet, the tubes being positioned within a housing, the combination of: an annular body member adapted to be removably secured to an open end of the housing, said body member having a cylindrical bore, a sleeve member mounted for axial movement within said bore relative to the body member and provided with an annular flange extending radially inwardly, means for establishing a sealed connection between said flange and an exposed side face of the tube sheet, said means including cooperating parts on the body member and sleeve

member for moving the sleeve member axially toward the tube sheet, and means for establishing a fluid-tight joint between the sleeve member and the body member independently of their relative axial positions.

4. In a device for pressure testing the tubes of a heat exchanger and for locating defective joints between the tubes and a tube sheet, the tubes and tube sheet projecting from the open end of a housing, the combination of: an annular body member adapted to be removably secured to the housing, a sleeve member mounted for axial movement relative to the body member and having an annular axially-extending projection encircling the tube sheet, an annular flange extending radially inwardly from the projection to encompass an annular portion of the tube sheet, means to provide a sealed connection between the annular flange and an exposed side face of the tube sheet, and means for establishing a fluid-tight joint between the sleeve projection and the body member.

5. In a device for pressure testing the tubes of a heat exchanger and for locating defective joints between the tubes and a tube sheet, the tubes and tube sheet projecting from the open end of a housing, the combination of: an annular body member adapted to be removably secured to the housing, a sleeve member mounted for axial movement relative to the body member and having an annular axially-extending projection encircling the tube sheet, an annular flange extending radially inwardly from the projection to encompass an annular portion of the tube sheet, means to provide a sealed connection between the annular flange and an exposed side face of the tube sheet, the major portion of the exposed side face of the tube sheet being exposed for

inspection through the opening in said annular flange, packing means encircling the sleeve projection for establishing a fluid-tight joint between the sleeve projection and the body member, and means including a movable element on the sleeve member for expanding the packing means.

5. In a device for pressure testing the tubes of a heat exchanger and for locating defective joints between the tubes and a tube sheet, the tubes and tube sheet projecting from the open end of a housing, the combination of: an annular body member adapted to be removably secured to the housing, a sleeve member mounted for axial movement relative to the body member, annular sealing means adapted to form a fluid-tight connection between said members independently of their relative axial position, an annular flange on the sleeve member extending radially inwardly to encompass an annular portion of the tube sheet, sealing means interposed between the annular flange and an exposed side face of the tube sheet, the major portion of the exposed side face of the tube sheet being exposed for inspection through the opening in said annular flange.
